Primary Examiner — Lakiya G Rogers*Assistant Examiner* — Carissa C Fitts(74) *Attorney, Agent, or Firm* — Wayne & Ken, LLC; Tony Hom(57) **CLAIM**

The ornamental design for a combined light and speaker, as shown and described.

DESCRIPTION

FIG. 1 is a front elevational view of a combined light and speaker showing my new design;

FIG. 2 is a rear elevational view thereof;

FIG. 3 is a left side view in enlarge scale thereof;

FIG. 4 is a right side view in enlarge scale thereof;

FIG. 5 is a top plan view in enlarge scale thereof;

FIG. 6 is a bottom plan view in enlarge scale thereof; and,

FIG. 7 is a perspective view thereof.

The broken lines shown in combined light and speaker form no part of the claimed design.
